UNITED STATES PATENT OFFICE.

HENRY B. BUCKHAM, OF CHICAGO, ILLINOIS, ASSIGNOR TO THE ALLBRIGHT-NELL COMPANY, OF CHICAGO, ILLINOIS, A CORPORATION OF ILLINOIS.

MACHINE FOR WASHING EDIBLE ANIMAL TISSUES.

Application filed December 27, 1920. Serial No. 433,086.

To all whom it may concern:

Be it known that I, HENRY B. BUCKHAM, a citizen of the United States, residing in Chicago, in the county of Cook and State of Illinois, have invented a new and useful Improvement in Machines for Washing Edible Animal Tissues, of which the following is a specification.

This invention relates to a machine for washing edible animal tissues and has for an object the provision of a machine of this nature that is simple and economical in construction, efficient in operation, and that affords a quick and ready discharge of the tissues which have undergone a washing treatment in the machine.

In addition to the general objects recited above, the invention has for further objects such other improvements or advantages in construction and operation as are found to obtain in the structures and devices herein-after described or claimed.

In the accompanying drawings forming a part of this specification, and showing, a preferred form and manner in which the invention may be embodied and practiced, but without limiting the claimed invention specifically to such illustrative instance or instances:

Figure 1 is a sectional elevation of a washing machine constructed in accordance with the present improvements;

Figure 2 is an end view thereof looking from the left hand end of Figure 1;

Figure 3 is an end view looking from the right hand end of Figure 1;

Figure 4 is a transverse vertical section of the machine;

Figure 5 is a view similar to Figure 4 showing the parts in position for dumping the treated tissues.

The same characters of reference indicate the same parts in each of the several views of the drawings.

The machine of the present invention is especially constructed for washing edible animal tissues, such as sweetbreads and the like, and for convenience the present description will be confined to this use of the invention. Features of construction and operation are, however, adaptable to other

valuable applications; consequently, the scope of the invention is not confined to the specific use and specific embodiment herein described as an illustrative example. 55

Referring to the drawings, the machine embodies in its construction a substantially cylindrical casing 11 supported at its opposite ends by means of pedestals 12 and 13. A section 14 of the casing wall is hinged at 60 15 to the main body of the casing, so as to provide a hinged cover which may be opened to deposit the material to be treated into the interior of the casing and closed during the period of the treatment of the material. 65 The opposite end plates 16 of the casing 11 are provided with bearings 17 which respectively support stub shafts 18 projecting from the opposite end plates 19 of a drum 20 revolvably mounted within the casing 11. 70 The left hand stub shaft 18 of the drum 20, as viewed in Figure 1, projects through the bearing 17 and is provided at its outer end with a large driven gear 21. This gear 21 is enmeshed with a small driving gear 22 75 on a parallel driving shaft 23, the latter receiving its power from pulley connections 24 of any preferred type.

As shown, the drum 11 is of substantially cylindrical form, being constituted of a foraminous or perforate cylindrical wall having a hollow interior within which are deposited the animal tissues to be treated. Secured to the interior of the drum 11 and extending in a direction parallel with its 85 axis are blades or scrapers 36. These blades or scrapers are located at convenient distances around the interior of the drum and project inwardly therefrom, so that they act to carry the material being treated 90 around the inner surface of the drum, so as to expose all parts of the material to the cleansing action and effect a thorough agitation of the material during the washing operation. In order to permit ready and 95 convenient charging of the drum with the material, as well as discharging of the treated material from the drum, as will hereinafter appear, a portion of the perforate cylindrical wall of the drum is formed 100 of removable sections 25. One longitudinal edge of the main body portion of the drum

is formed with a plurality of spaced pairs of lugs 26 having aligned holes 27. The lateral arcuate edges 28 of the removable sections 25 are respectively constituted of bands 5 projected beyond the outer faces of the removable sections, as shown in Figure 4, and also extending beyond the upper longitudinal edges 29 of the removable sections. The so extended portions of the bands 28 are cut 10 into the form of pairs of lugs 30 that are respectively adapted to receive a lug 26 of the main body portion of the drum. The lugs 30 are formed with holes adapted to align the holes 27 of the lugs 26, when the removable sections 25 are positioned to close the drum. As shown in Figure 4, the ends of the bands 28, opposite to the lugs 30, are inturned to rest upon the bottom contiguous edge of the main portion of the drum and to 15 lock behind said edge when the removable sections 25 are positioned on the drum. When the removable sections 25 are positioned on the drum, pins 31 are inserted through the aligned holes of the interlocked 20 ears 26 and 30 to retain the removable sections in position with respect to the main body portion of the drum.

Extending along in front of the casing 11 and just below the bottom edge of the hinged 25 cover 14 is an inclined trough 32 connected at its discharge end with a discharge pipe 33. Wash water and other matter spilled out of the drum may discharge through the trough 32 and be carried away by the pipe 33. Formed in the bottom of the casing 11 is an 30 inclined discharge trough 34 for the material. The upper end of said trough 34 is provided with pipes 35 through which a supply of steam and water is introduced into the 35 interior of the casing during the treatment of the material, and the lower end of the trough is provided with a manually operable gate 36 which may be opened when discharging the treated material and closed 40 during the treatment of the material. The wash water discharges through a pipe 37 leading from the trough at a point near its lower end.

In operating the machine, the casing is 45 opened by swinging up the cover 14 and the drum is then rotated so that the removable sections thereof are in position behind the open portion of the casing. The sections are then removed, and the tissue to be treated 50 is deposited in the drum. The removable sections of the drum are then re-applied, the cover of the casing is closed and the steam is turned on into the steam supply pipes 35. The drum is then rotated for the desired 55 period of time to thoroughly cleanse the material and when the cleansing operation has been completed, the rotation of the drum is stopped, the cover 14 is again opened, and the removable sections 25 of the drum are 60 again removed. When this has been accom-

plished, the drum is rotated so that the portion from which the sections 25 have been removed is in registry with the top of the trough 34. The washed tissue then discharges into the trough 34 and may, by the application of wash water through the pipes 35, be washed out through the gate 36.

The invention as hereinabove set forth is embodied in a particular form of construction, but may be variously embodied within 75 the scope of the claims hereinafter made.

I claim:

1. A machine for washing edible animal tissues, comprising in combination: a casing, a discharge trough communicating with the bottom of said casing, a drum revolubly mounted within said casing, said drum being provided with a removable section, whereby material may be deposited in the drum and by a subsequent rotary movement of the drum discharged into said trough, and means located beneath said drum and within the upper end of said trough for cleansing said material during the rotary movement of the drum, said cleansing means being further operable to discharge the washed material from said trough after it has been discharged from said drum.

2. A machine for washing edible animal tissues, comprising in combination: a casing, a discharge trough communicating with the bottom of said casing, a drum revolubly mounted within said casing, said drum being provided with a plurality of plates projecting inwardly from its inner surface and having a removable portion, whereby material to be washed may be deposited in the drum and by a subsequent rotary movement of the drum discharged into said trough and steam and water pipes communicating with the upper end of said trough for cleansing said material during the rotary movement of the drum, said cleansing means being further operable to discharge the washed material from said trough after it has been discharged from said drum.

3. A machine for washing edible animal tissues, comprising in combination: a casing, a discharge trough communicating with the bottom of said casing, a drum revolubly mounted within said casing, said drum being provided with a plurality of plates projecting inwardly from its inner surface and having a removable portion, whereby material to be washed may be deposited in the drum and by a subsequent rotary movement of the drum discharged into said trough, and means at the upper end of the trough for cleansing said material during the rotary movement of the drum, said cleansing means being further operable to discharge the washed material from said trough after it has been discharged from said drum.

4. A machine for washing edible animal

tissues, comprising in combination: a casing, a discharge trough communicating with the bottom of said casing, a drum revolvably mounted within said casing, said drum being provided with a plurality of plates projecting inwardly from its inner surface and having a removable portion, whereby material to be washed may be deposited in the

drum and by a subsequent rotary movement of the drum discharged into said trough, ¹⁰ means for introducing steam to the interior of the drum and means for introducing water at the upper end of the trough for ejecting the washed material.

HENRY B. BUCKHAM.
